DESIGN FOR A UTILITY CABINET

Woodrow M. Hockman and Kenneth F. Hockman, Lansdale, Pa.

Application November 26, 1938, Serial No. 81,386

Term of patent 7 years

To all whom it may concern:

Be it known that we, Woodrow M. Hockman and Kenneth F. Hockman, citizens of the United States, residing at Lansdale, in the county of Montgomery and State of Pennsylvania, have invented a new, original, and ornamental Design for a Utility Cabinet, of which the following is a specification, reference being had to the accompanying drawings, forming part thereof.

We claim:

The ornamental design for a utility cabinet, as shown.

WOODROW M. HOCKMAN.
KENNETH F. HOCKMAN.
